UNITED STATES PATENT OFFICE

160,249

RUNOUT BIT

George H. Collins, Lynbrook, N. Y.

Application August 16, 1949, Serial No. 4,541

Term of patent 14 years

(D38-2)

To all whom it may concern:

Be it known that I, George H. Collins, a citizen of the United States, residing at Lynbrook, Nassau County, New York, have invented a new, original, and ornamental Design for a Runout Bit, of which the following is a specification, reference being had to the accompanying drawings, forming a part hereof.

Fig. 1 is a side elevational view of a runout bit, showing my new design.

Fig. 2 is a sectional view taken on the lines 2—2 of Fig. 1.

Fig. 3 is a left side elevational view.

Fig. 4 is a right side elevational view.

Fig. 5 is a plan view of the runout bit in partial

operative position so as to bring out the design in further detail.

I claim:

The ornamental design for a runout bit, as shown.

GEORGE H. COLLINS.
